UNITED STATES PATENT OFFICE.

GEORGE WILLIAM JONES, OF BROOKLYN, NEW YORK.

UMBRELLA OR PARASOL.

SPECIFICATION forming part of Letters Patent No. 334,588, dated January 19, 1886.

Application filed May 29, 1884. Renewed December 9, 1885. Serial No. 185,164. (No model.)

To all whom it may concern:

Be it known that I, GEORGE WILLIAM JONES, of Brooklyn, in the county of Kings and State of New York, have invented a new and useful Improvement in Self Opening and Closing Umbrellas or Parasols, of which the following is a full, clear, and exact description.

Reference is to be had to the accompanying drawings, forming a part of this specification, in which similar letters of reference indicate corresponding parts in all the figures.

Figure 1 is a sectional side elevation of the frame of one of my improved umbrellas shown open and part being broken away. Fig. 2 is a side elevation of the upper part of the same shown closed and part being broken away. Fig. 3 is a side elevation of the lower part of the same shown closed and with the outer tube drawn down. Fig. 4 is a sectional plan view of the same, taken through the line *xx*, Fig. 3. Fig. 5 is a sectional plan view of the same, taken through the line *yy*, Fig. 3.

The object of this invention is to promote convenience in opening and closing umbrellas or parasols.

The invention consists in the combination, with the ribs and braces and their runners, of a hollow stick having a rod sliding therein and connected by a wire with a slotted tube sliding upon the lower end of the hollow stick and provided with an exterior sliding tube having a cross-pin passing through the slot of the interior tube, a spring interposed between the cross-pin and the end of the stick, a spring interposed between shoulders upon the rod and hollow stick, and spring-catches connecting the two tubes and the inner tube and hollow stick, whereby the umbrella or parasol can be opened and closed by the action of the said springs.

Telescopic braces and their runner are connected with the ribs, the braces and their runner, and the hollow stick, to hold the ribs from being forced too far back, as will be hereinafter fully described.

A represents the stick of the umbrella or parasol, which is made hollow, and in its upper part slides a rod, B, having a cap-ferrule, C, attached to its upper end to cover the runner D, attached to the said rod and the central opening in the cover. The cover is not shown

in the drawings, as there is nothing new in its construction.

To the upper runner, D, are hinged the inner ends of the ribs E, to which near their inner ends are hinged the outer ends of short braces F. The inner ends of the braces F are hinged to the intermediate runner, G, which is attached to the hollow stick A, near its upper end. The braces F control the movements of the ribs E. The ribs E are held from turning too far back by the extension or telescopic braces H, the outer ends of the outer parts of which are hinged to the ribs E, and the inner ends of their inner parts are hinged to the lowest runner, I. The outer parts of the braces H slide in the inner parts, and are held from drawing out of the said inner parts by pins J, which pass through slots in the said inner parts and are attached to the inner ends of the said outer parts, as shown in Fig. 1. The runner I is attached to the hollow stick A at a little distance from the runner G. The inner part of the rod B is reduced in size, and upon it is placed a spiral spring, K, the upper end of which rests against the shoulder of the said rod B, and its lower end rests against a shoulder in the inner surface of the hollow stick A, at the inner end of the countersink formed in the said stick to receive the longer part of the rod B.

To the lower end of the rod B is attached the upper end of the wire L, the lower end of which is attached to the closed lower end of the tube M, the upper end of which is placed upon the lower end of the hollow stick A.

Within the tube M is placed a strong spiral spring, N, the upper end of which rests against the lower end of the stick A, and its lower end rests against a cross-pin, O. The ends of the cross-pin O pass through a slot in the lower part of the tube M, and are secured to the middle part of the tube P, which is closed at its lower end. The upward movement of the tube P upon the tube M is limited by a shoulder formed upon the upper end of the said tube M.

To the inner surface of the upper end of the tube P is attached a catch, Q, with which engages a spring-latch, R, attached to the outer surface of the upper part of the tube M. The upper end of the spring-latch R is bent out-

ward and is covered with a spring thumb-piece, S, attached to the upper end of the said tube M, so that by pressing inward upon the spring thumb-piece S, when the various parts 5 are in the position shown in Fig. 1, the latch R will be disengaged from the catch Q, allowing the tube M and its attachments to be forced upward by the spring N and relaxing the tension of the said spring, so that the spring K 10 can force the rod B upward within the stick A. The upward movement of the rod B carries the runner D and the inner ends of the ribs E with it, drawing the upper ends of the braces F inward toward the rod B, and swinging 15 the ribs E inward against the stick A, closing the umbrella or parasol. The tube P is then pushed upward upon the tube M, and the two tubes are pushed upward upon the stick A, compressing the spring N and 20 leaving the umbrella or parasol ready to be opened when required. The tube M, when pushed upward upon the stick A, is held in place by the spring-latch T, which engages with the catch-pin U, attached to the inner 25 surface of the upper end of the said tube M. When the umbrella or parasol is to be opened, the spring-latch T is pushed inward, disengag-

ing it from the catch-pin U and allowing the spring N to force the stick A upward, and thus expand the ribs E.

30

Having thus described my invention, I claim as new and desire to secure by Letters Patent—

1. In an umbrella or parasol, the combination, with the ribs E, braces F, and runners D G, of the hollow stick A, the rod B, the slotted 35 interior tube, M, the exterior tube, P, the connecting-wire L, the cross-pin O, the two springs N K, and the spring-catches Q R and T U, substantially as herein shown and described, whereby the umbrella or parasol can 40 be opened and closed by the action of the said springs, as set forth.

2. In a self opening and closing umbrella or parasol, the combination, with the ribs E, the braces F, and runner G, and the hollow stick 45 A, of the telescopic braces H, and the runner I, substantially as herein shown and described, whereby the said ribs will be held from being forced too far back, as set forth.

GEORGE WILLIAM JONES.
